United States Patent Office

JOHN A. SNYDER, OF GEORGETOWN, PENNSYLVANIA.

Letters Patent No. 73,844, dated January 28, 1868.

IMPROVEMENT IN MACHINES FOR MORTISING FENCE-POSTS AND SHARPENING FENCE-RAILS.

The Schedule referred to in these Letters Patent and making part of the same.

TO ALL WHOM IT MAY CONCERN:

Be it known that I, JOHN A. SNYDER, of Georgetown, county of Northumberland, and State of Pennsylvania, have invented a new and useful Improvement in Machines for Sawing and Mortising Fence-Rails and Posts; and I do hereby declare that the following is a full, clear, and exact description of the construction and operation of the same, reference being had to the annexed drawing, making a part of this specification, in which—

Figure 1 is a plan or top view of my improved post-and-rail-fence machine.

Figure 2 is a side elevation of the same.

Similar letters of reference denote corresponding parts in both figures.

My invention consists in a novel arrangement of adjustable carriages and guide-ways in connection with a circular saw, and with boring and mortising-devices, for the purpose of conveniently sawing or pointing fence-rails, and boring and mortising the posts to be used therewith, as will be hereinafter explained.

In the accompanying drawings, A represents an upright frame or table, of any suitable construction and height to adapt it to the purpose hereinafter set forth, and provided with suitable bearings a, in which is mounted a driving-shaft, to which motion is imparted in any usual or desired manner. B is a ground-extension of the frame A, consisting of two longitudinal bars or ways, hinged or otherwise connected at one end to said frame, and united at their outer ends by the transverse bar or tie b; and C is a vertical frame or carriage, of about the same height as frame A, provided with friction-rollers or wheels, arranged to rest upon and to move back and forth upon the longitudinal bars or ways of the frame-extension B. C' is a horizontal arm, attached to the reciprocating frame C, and arranged to work in a guiding-mortise or way in frame A, and which serves to steady frame C in its movements, and to maintain it in proper working relation to frame A. Additional steadyng-arms may be used, if found desirable. The top bar of frame C is slotted in the direction of its length, the slot (marked c¹) being curved in the arc of a circle, centring in the saw-table, hereinafter referred to, and has secured to it, for convenience in construction, a divided plate, c², the two parts of which slightly overlap the mortise, and conform, on their adjacent faces or edges, to the curvature of the mortise, as shown in fig. 1. D is an adjustable bar or plate, provided on its under surface with a curved rib, which also conforms in shape to the curvature of the mortise C', and to which is secured a metal plate, d, arranged to overlap the rib, and to work underneath the opposing parts of the divided plate c², or a curved metal rail of T-form, in cross-section, may be secured in an inverted position to bar D, if preferred. D' is an upright swivelled in bar D, in such manner as to turn freely therein, and provided, at a convenient point in its height, with an adjustable clamp, d', for holding the rail while subjected to the action of the saw for pointing, as hereinafter set forth. E is a saw-carriage or frame, hinged at e to the frame A, and provided with suitable bearings, in which is mounted an endless belt from the main axle or shaft a. The saw, when in operation, is raised into the position shown in black lines, fig. 2, working through a slot, g, in the saw-table G, (see fig. 1,) and, when not in use, may, if desired, be removed from the table, and depressed into position, shown by red lines, fig. 2, when, by the approach of its shaft toward the main driving-shaft, the belt is slackened, and the saw ceases to rotate. When raised, the saw-frame is sustained in working position by means of hooks e', or other equivalent device.

H is a horizontal shaft, mounted in suitable bearings h' on frame A, and armed with a pulley H', to which motion is communicated from shaft a. The inner end of the shaft H is provided with a bit-stock, adapted to receive bits for boring the posts, as hereinafter explained. I is a horizontal frame, mounted in longitudinal ways or rebates formed in the upper longitudinal bars of frame A, and upon one end of which the slotted saw-table G is secured. One of the longitudinal bars of frame I is provided with a toothed rack on its under surface, into which a spur-wheel on shaft i¹ gears, and by means of which a longitudinal reciprocating movement is imparted, when desired, by means of crank or crank-wheel i², (see fig. 2.) i i are transverse bars of frame I, which are rebated, or provided with plates overlapping their adjacent faces, to afford ways for a second horizontal and transversely-adjustable frame, K, the outer bars of which are grooved (at k) or otherwise adapted

H is a horizontal shaft, mounted in suitable bearings h' on frame A, and armed with a pulley H', to which motion is communicated from shaft a. The inner end of the shaft H is provided with a bit-stock, adapted to receive bits for boring the posts, as hereinafter explained. I is a horizontal frame, mounted in longitudinal ways or rebates formed in the upper longitudinal bars of frame A, and upon one end of which the slotted saw-table G is secured. One of the longitudinal bars of frame I is provided with a toothed rack on its under surface, into which a spur-wheel on shaft i¹ gears, and by means of which a longitudinal reciprocating movement is imparted, when desired, by means of crank or crank-wheel i², (see fig. 2.) i i are transverse bars of frame I, which are rebated, or provided with plates overlapping their adjacent faces, to afford ways for a second horizontal and transversely-adjustable frame, K, the outer bars of which are grooved (at k) or otherwise adapted

to work back and forth on ways or guides i . K' is a table, mounted on the frame K . The bars K of said frame, either one or both, are provided with toothed racks L , which mesh into and are reciprocated by means of pinions on horizontal shaft L' . The shaft L' is provided with an additional spur-wheel, by means of which it is rotated through a rack, M , toothed upon the bottom, and upon one of its sides, and operated by the horizontal pinion m on the vertical crank-shaft m' , mounted in any suitable manner on frame or carriage I . N are uprights, mounted in the reciprocating frame K , and provided with clamps or clamping-devices for holding the posts while subjected to the action of the bit.

By this construction, it will be seen that the frame K is rendered adjustable in paths at right angles to each other, as follows, viz, transversely of frame A , and of the carriage or frame I , by means of the transversely reciprocating carriage K , operated by crank-shaft m' and the connecting mechanism described, or its equivalent, and longitudinally of frame A with frame or carriage I , by means of shaft i' , in the manner described. In this way the posts (one of which is represented at O in the drawing) are firmly held by clamps on the upright or carriage K while being presented to the bit, and adjusted back and forth into proper position for boring for the several mortises therein.

P is a mortising-chisel, mounted in a vertically-reciprocating carriage, P' , which is arranged to work up and down on suitable ways in the framing Q , attached to one corner of frame A , and which is operated by means of a cam-lever, R , pivoted at r in the frame Q , (see fig. 2.) The chisel P is made in size and form to correspond with the mortise to be cut in the posts, in such manner that the mortise, after the posts have been properly bored, is completed by a single stroke of the chisel. If preferred, however, the ordinary mortising-chisel may be used.

The pointing of the rails is effected as follows: The said rail (which is represented in the drawings at D^2) is secured at or near its centre, in the clamp d' on the swivelling-post D^1 , when, by the longitudinal adjustment of said bar in its curved track, and the swivelling of the post mounted therein, the rail is brought into the desired angle of relation to the circular saw, and the forward movement of carriage C presents the rail to the saw, and it is cut as desired. The point having been thus cut upon one end of the rail, is turned end for end, without the necessity of being removed from the holding-clamp, by means of the swivelling-standard, and the other end is pointed or curved in the same manner. The operation of the other parts has been described in connection with the description of their construction, and need not be further referred to here.

It will be apparent that changes may be made in the construction of some of the parts of the machine, as in the holding-clamps, and the particular arrangement of the means for operating the reciprocating carriage, without departing from my invention.

Having now described the construction and operation of my improved machine for pointing and mortising fence-rails and posts, what I claim, and desire to secure by Letters Patent, is—

1. The rail-carriage, consisting of the adjustable bar D , mounted on the upright reciprocating carriage C , and provided with the swivelling-clamp standard D' , the whole constructed and operating in the manner and for the purpose set forth.
2. The reciprocating rail-carriages I and K , adapted to be moved in paths at right angles to each other, in combination with the toothed racks and pinions for operating said carriages, the whole arranged and operating as described.

JOHN A. SNYDER.
